UNITED STATES PATENT OFFICE.

RALPH L. SKINNER, OF DETROIT, MICHIGAN, ASSIGNOR TO SKINNER AUTOMOTIVE DEVICE CO., INC., OF SACRAMENTO, CALIFORNIA, A CORPORATION OF CALIFORNIA.

INTERNAL-COMBUSTION-ENGINE CONSTRUCTION.

Application filed July 21, 1922. Serial No. 576,516.

To all whom it may concern:

Be it known that I, RALPH L. SKINNER, a citizen of the United States, residing at Detroit, in the county of Wayne and State 5 of Michigan, have invented certain new and useful Improvements in Internal-Combustion-Engine Constructions, of which the following is a specification.

My invention relates to improvements in 10 internal-combustion engines or motors and similar appliances equipped with means for drawing off fluids from around the reciprocatory pistons, such as the removal by suction of the excess lubricating oil and the 15 gaseous or liquid fuel and products of combustion escaping past the pistons, whereby to effect an economy in oil consumption, the withdrawn oil being reclaimed and returned to the oiling system, and to bring about a 20 prevention of dilution or contamination of the oil supply by reason of the removal of such escaping fuel and combustion products, and to effect a fuel saving by returning to the engine the abstracted fuel after separation 25 from the oil.

This general plan is not now new, but this invention concerns more particularly or especially an improved piston arrangement in such a system.

To this end, instead of having a separate 30 oil-collecting groove surrounding the outer surface of each piston below and adjacent to its piston rings, in the new structure one of the piston-ring grooves in the piston is employed for this purpose, other parts being 35 slightly changed to effect the performance of the desired functions.

To enable those skilled in this art to have 40 a full and complete understanding of this invention and its various advantages and benefits, I have illustrated in the accompanying drawings, forming a part of this specification, a desirable and preferred embodiment of the invention, like reference 45 characters being used for the same parts throughout the several views.

In these drawings:

Figure 1 is a fragmentary side elevation 50 of an internal-combustion engine fitted with this system;

Figure 2 is a plan view of the construction shown in Figure 1;

Figure 3 is an end elevation of the same engine;

Figure 4 is a broken view through one 55 of the engine cylinders and its piston;

Figure 5 is a fragmentary section through the wall of one of the pistons showing the piston-ring groove employed as a fluid-collecting means; and

Figure 6 is an elevation of one of the pistons.

Referring to these drawings, it will be seen that each one of the plurality of pistons 11 of the six-cylinder engine depicted 65 has a number of parallel piston-ring grooves 102, 103 and 104 around its upper end, such grooves accommodating the corresponding expandable piston-rings 105, 106 and 107.

If preferred or necessary, the lower piston-ring 107 may have an annular cavity or recess 108 provided in its inner surface whereby to supply adequate space between the piston-ring and the inner wall of its groove.

Each piston 101 has a downward extension 109 extended beyond the normal lower edge of its skirt at one side only thereon, and, in register with such projection, the outer surface of each piston has a longitudinal groove 111 connected to the inner portion of the piston-ring or fluid collecting groove 104 inwardly of the piston-ring by the right angle passage or channel 112 and 113.

Diametrically opposite the channel 111—112—113, such piston-ring groove 104 is supplied with a vent or air inlet hole 114 extending from the piston-ring groove through the piston wall to the hollow interior of the piston.

Each engine cylinder 115, water-jacketed at 116 at its upper part if the engine is of the water-cooled type, has a port 117 extended therethrough in register with the 95 piston groove 111 and the skirt extension 109, such port being in communication with the groove when the latter is opposite the port and closed at other times by the skirt of the piston and the extension.

Each of such several cylinder ports of the multi-cylinder engine is connected by a pipe 118 to a pipe 119 common to all of them, and the middle portion of such latter pipe

100

is connected to the lower part of a heater 122 by a pipe 121 extended around an end of the motor.

This heater 122 has an inner chamber to 5 the lower end of which the pipe 121 is connected and the upper end of such internal chamber or compartment is connected by a pipe 123 to the top of a separating-tank 124 the bottom of which by an oil delivery pipe 10 125 is in communication with the engine sump, the top of such tank being also fitted with a pipe connection 126 to the intake-manifold or carburetor connection 127 of the engine, whereby the withdrawn fuel may be 15 returned for consumption in the engine.

The outer or heating compartment, which surrounds the inner one of the heater 122, is connected at 128 to the exhaust-manifold 129 of the engine and the lower portion of 20 such outer or exhaust gas jacket is connected at 131 to an appropriate exhaust-pipe 132.

When each piston during its reciprocation brings its external groove 111 into register with its cylinder port 117, such groove 25 will be subjected to the suction of the intake-manifold by reason of the connections 118, 119, 121, 122, 123, 126 and 127, whereby the piston-ring groove 104, and particularly that portion of it inside of the piston-ring, 30 will be submitted to sub-atmospheric pressure, so that the accumulated fluids therein and around the piston-ring will be drawn or sucked out through the pipe connections specified and delivered into the separator 35 124 in which the oil is separated and reclaimed from the other products and delivered through the pipe 125 into the engine sump, whereas the gaseous and gasified products brought into gaseous or vapor form by 40 reason of the action of the heater 122 are drawn through the pipe 126 into the intake-manifold, where they pass with the explosive mixture from the carburetor into the cylinders for combustion.

45 To facilitate the quick delivery of the fluids in the several piston-ring grooves into the piping system specified, the air-vents 114 are of material assistance, and it should be borne in mind that the piston-rings are sufficiently loose in their grooves to permit the 50 passage of gases and oil around them into the inner portions of such grooves for withdrawal in the manner specified.

The invention is susceptible of a variety 55 of embodiments in satisfactory form, but the one shown and described is the present preferred one.

It should be borne in mind, however, that many minor mechanical changes may be 60 made in such structure without departure from the heart and essence of the invention and without the sacrifice of any of its substantial and material benefits and advantages.

65 It will be noted that, in earlier structures

of this general type having a separate or special oil-collecting groove around the piston below its piston-ring grooves, the oil and other fluids in such supplemental groove, while being subjected to the withdrawing 70 suction, are also more or less in contact with the inner surface of the cylinder wall with relation to which they are travelling at right angles to the direction of flow of the suction, resulting in a decreased efficiency in the 75 oil removing action, but in the present device, since the oil and other fluids are withdrawn from beneath or inside of the piston-ring, where they have a more or less natural tendency to accumulate because of the re- 80 ciprocation of the piston, and where they are not subjected to the action of the relative travel between the piston and the cylinder, a more efficient and effective withdrawal under subatmospheric pressure is readily at- 85 tained.

Since the lower piston-ring groove only is arranged to act in the manner stated, the other or upper piston-rings maintain adequate compression of the explosive gaseous 90 mixture in the firing chamber above the piston.

In some cases, where the cylinder is of relatively large bore and the piston of correspondingly great diameter, it may be desirable to withdraw the fluids from the groove at a plurality of points.

No specific means has been shown for supplying the lubricating oil to the piston and cylinder since this is well understood in the 100 art and may be readily accomplished by the ordinary splash or force feed system.

I claim:

1. The combination of a piston having a piston-ring groove and a piston-ring in said 105 groove, said piston having a groove on its exterior disposed longitudinally of the piston and in communication with said piston-ring groove inwardly of the piston-ring.

2. The combination of a piston having a plurality of piston-ring grooves, and piston-rings in said grooves, said piston having a groove on its exterior disposed longitudinally of the piston and in communication with the lower one of said piston-ring 115 grooves, inwardly of its piston-ring.

3. A piston having a piston-ring groove and a groove on its exterior disposed longitudinally of the piston and in communication with the inner portion of said piston-ring groove.

4. A piston having a piston-ring groove, a groove on the exterior of the piston in communication with said piston-ring groove, and an air-port connected with said piston-ring groove substantially opposite said external groove and extending inwardly through the piston-wall, in combination with a piston-ring in said piston-ring groove.

5. A piston having a piston-ring groove 130

and a groove on the exterior of the piston in communication with said piston-ring groove, in combination with a piston-ring in said latter groove having an annular recess in 5 its inner face.

6. In an appliance of the character described, the combination of a cylinder having a port, means to apply suction to said port, a piston reciprocatory in said cylinder 10 having a piston-ring groove, a piston-ring in said groove, means to supply lubricating oil to said cylinder and piston; and means to apply the suction at said port to said piston-ring groove to withdraw its fluid contents during at least a portion of the travel 15 of the piston.

7. In an appliance of the character described, the combination of a cylinder having a port, means to apply suction to said 20 port, a piston reciprocatory in said cylinder having a piston-ring groove and a groove on its exterior in communication with said piston-ring groove and in register with and adapted to connect with said port during its 25 reciprocation, a piston-ring in said piston-ring groove, and means to supply lubricating oil to said cylinder and piston, whereby such suction withdraws the fluid contents of said piston-ring groove.

30 8. In an appliance of the character described, the combination of a cylinder having a port, means to apply suction to said

port, a piston reciprocatory in said cylinder having a piston-ring groove and a groove on its exterior in communication with said piston-ring groove and in register with and adapted to connect with said port during its reciprocation and an air inlet passage extended through the wall of said piston and communicating with said piston-ring groove 35 substantially diametrically opposite said exterior groove, a piston-ring in said piston-ring groove, and means to supply a lubricant to said cylinder and piston.

9. In an appliance of the character described, the combination of a cylinder having a port, means to apply suction to said port, a piston reciprocatory in said cylinder having a plurality of piston-ring grooves and a groove on its exterior in communication with the lowermost of said piston-ring grooves and in register with and adapted to connect with said port during the reciprocation of the piston and an air inlet passage extended through the piston wall substantially diametrically opposite said exterior groove and communicating with said lowermost piston-ring groove, piston-rings in said piston-ring grooves, and means to supply lubricating oil to said cylinder and piston. 55 60

In witness whereof I have hereunto set my hand and seal.

RALPH L. SKINNER. [L.S.]
